CLIP FOR FOUNTAIN PENS AND OTHER ARTICLES

David Coyne, New York, N. Y.

Application February 21, 1945, Serial No. 579,064

4 Claims. (Cl. 24—11)

1

This invention relates to clips for fountain pens and other articles.

The primary object of the present invention is to provide a safety clip which is so constructed and related to the cap of the fountain pen that it affords improved means for retaining the pen in attached relation to the pocket of a garment in which the pen is usually carried. In this connection a more specific object of the invention is to provide a retaining clip or clasp which is so constructed as to greatly reduce or prevent impairment of the retaining function of the clip due to decrease in or loss of resiliency of the clip. For example, in one type of clip now widely used on fountain pen caps, a resilient member is fastened to one end of the cap and extends longitudinally of the cap in resilient engagement with or close to the side of the cap. It has been found, however, that after this type of clip has been used for some time, repeating flexing of the clip in attaching the pen to and detaching the same from the garment results in impairment of the retaining function of the clip due to the bending of the spring arm of the clip away from the side of the cap, said bending of the spring arm of the clip away from the side of the cap being accompanied by or resulting in decreased resiliency of said spring arm. This serious objection and disadvantage is eliminated by the clip of the present invention.

The above and other objects, features and advantages of the present invention will be fully understood from the following description considered in connection with the accompanying illustrative drawings.

In the drawings:

Fig. 1 is a side view of a fountain pen provided with a retaining clip embodying the present invention;

Fig. 2 is a view taken at right angles to Fig. 1;

Fig. 3 is a sectional view, on a larger scale, on the line 3—3 of Fig. 1;

Fig. 4 is a sectional view, on a larger scale, on the line 4—4 of Fig. 2.

Referring now to the drawings in detail, there is shown a fountain pen cap 10 which is attached in the usual way in covering relation to the pen carried by the fountain pen barrel, a part of which is indicated at 12 in Figs. 1 and 2. The retaining clip of the present invention comprises a resilient metal member 14 having a laterally extending end portion 16 attached to the closed end 18 of the cap 10 in any suitable way as by a screw 20 which passes through an opening 22 in lateral portion 16 of retaining member 14 and

2

is threaded into the end of cap 10. A second retaining member 24 has a laterally extending end portion 26 also secured, as here shown, to the closed end 18 of the cap by screw 20, said lateral end portion of member 24 being provided with an opening 27 through which the screw projects. For convenience in reference, members 14 and 24 may be termed inner and outer retaining members, respectively. The spring arm 28 of inner retaining member 14 is attached at a point between its opposite ends to a metal ferrule or ring 30 in any suitable way as by a rivet element 32, as illustrated in Fig. 3. If desired, ring 30 can be secured to cap 10 by a rivet 34 as illustrated, or in any other suitable way. Ring 30 is provided with a lateral projection 35 (Figs. 1 and 4) which holds spring arm 28 of inner retaining member 14 in spaced relation to the outer surface of cap 10 so that the gripping portion of said spring arm can flex toward the adjacent side portion of cap 10 when attached to the side of the pocket in which the pen is carried. Inner spring arm 28 is flexed or spring-biased, by its own resiliency, toward outer spring arm 36 in resilient engagement therewith. Outer retaining member 24 is formed of sheet metal and is less resilient than spring arm 28 of inner retaining member 14 so that when the side of the pocket is inserted between arm 28 of inner retaining member 14 and the confronting arm 36 of outer retaining member 24, spring arm 28 is flexed toward cap 10 below ring 30. As arm 36 of outer retaining member 24 is preferably stiffer than spring arm 28, said arm 36 does not easily bend away from cap 10. On the other hand, the inward flexing of spring arm 28 is limited by the engagement of the free end 38 of said arm with the side of cap 10 when the side wall of the pocket is positioned between inner and outer arms 28 and 36. Thus, both arms 28 and 36 resiliently engage the side wall of the pocket when said side wall is positioned between said two arms, although it will be understood that it is within the scope of the present invention to provide the outer retaining member 24 with no or negligible resiliency in its arm 36. Preferably, as illustrated the outer end portions, i. e., the gripping portions, of arms 28 and 36 have interfitting portions 39 and 40, respectively, to improve the grip of said arms on the part of the garment to which the clip is attached. Inner and outer retaining members 14 and 24 are preferably provided with means for holding them in relative position whereby to prevent relative lateral displacement of arms 28 and 36, or conversely, to maintain said arms in con-

fronting relation. Any suitable means may be provided for this purpose, for example, laterally extending end portion 16 of retaining member 14 may be provided with one or more recesses 42 in which projections 44 carried by the laterally extending portion 26 of outer retaining member 24 project.

While I have shown and described the presently preferred embodiment of my invention, it will be understood that the latter may be embodied otherwise than as herein specifically illustrated or described and that in the illustrated embodiment certain changes in the details of construction and in the arrangement of parts may be made without departing from the underlying idea of the invention within the scope of the appended claims. Also it will be understood that while the retaining clip of the present invention has been illustrated as applied to a fountain pen, said retaining clip can be used on pencils, thermometer cases, or other articles.

Having thus described my invention, what I claim and desire to secure by Letters Patent is:

1. A device of the class described comprising a cap, individually separate inner and outer retaining members having laterally extending end portions secured to each other and to one end of said cap and having confronting arms extending longitudinally of the cap, the arm of said inner member being spring-biased toward the arm of said outer member and arranged to be flexed laterally toward the adjacent side of the cap in resilient gripping relation with said arm of the outer member, and means positioned between the ends of the arm of said inner member for holding the gripping portion of said inner arm spaced from the adjacent side of the cap in position to be flexed toward said side of the cap.

2. A retaining device of the class described, comprising a pair of individually separate members having laterally extending attaching portions at their adjacent ends and having inner and outer confronting arms separable at their opposite ends, the portions of said arms adjacent said opposite ends being relatively flexible toward and away from each other in resilient article-gripping relation and said outer arm being less

flexible than said inner arm, and interengaging means on said laterally extending end portions of said members for holding said arms in said confronting relation.

5 3. A device of the class described comprising a cap, individually separate inner and outer retaining members having laterally extending end portions secured to each other and to one end of said cap and having confronting arms extending longitudinally of the cap, the arm of said inner member being spaced from the adjacent side of the cap and spring-biased toward the arm of said outer member and arranged to be flexed laterally toward the adjacent side of the cap in resilient gripping relation with said arm of the outer member, said inner arm being more easily flexible than said outer arm.

10 4. A device of the class described comprising a cap, individually separate inner and outer retaining members having laterally extending end portions secured to each other and to one end of said cap and having confronting arms extending longitudinally of the cap, the arm of said inner member being spring-biased toward the arm of said outer member and arranged to be flexed laterally toward the adjacent side of the cap in resilient gripping relation with said arm of the outer member, said inner arm being more easily flexible than said outer arm, and means positioned between the ends of the arm of said inner member for holding the gripping portion of said inner arm spaced from the adjacent side of the cap in position to be flexed toward said side of the cap.

15 35 DAVID COYNE.
